By his Attorney
Fred Parker.*

UNITED STATES PATENT OFFICE.

NEWELL D. PARKER, OF NEW YORK, N. Y., ASSIGNOR TO STANDARD SCIENTIFIC COMPANY, OF NEW YORK, N. Y., A CORPORATION OF NEW YORK.

SUPPORTING-CLAMP FOR VARIOUS OBJECTS.

1,311,089.

Specification of Letters Patent. Patented July 22, 1919.

Application filed September 28, 1916. Serial No. 122,617.

To all whom it may concern:

Be it known that I, NEWELL D. PARKER, a citizen of the United States, and resident of New York, in the county of New York and State of New York, have invented certain new and useful Improvements in Supporting-Clamps for Various Objects, of which the following is a specification, reference being had therein to the accompanying drawings.

This invention refers to a clamping device for supporting objects of various kinds in any desired position, such objects for example as maps, charts, pictures, articles of wearing apparel, and a multitude of other things which need not be enumerated. The object of the invention is to provide a secure and effective clamping means which can be readily brought into use for the purpose of clamping and holding the object, and can be disengaged with equal facility so as to release the object when desired.

In the accompanying drawings illustrating my invention:

25 Figure 1 is a perspective view of my improved clamping device for supporting various objects.

30 Fig. 2 is a sectional side elevation showing the use of one of the cam devices of the clamping member.

The frame of the clamp consists of a rear attaching plate 1 adapted to be secured to a suitable support such as the face of a wall by means of screws 2 or other securing means. Extending from the upper end of the plate and preferably from the opposite edges thereof are a pair of parallel bracket arms 3 preferably of inverted L shape, the horizontal members being designated 7 and the vertical members 8, these latter being parallel with the attaching plate 1. In the lower ends of the depending parts of the bracket arms is supported, upon a pivot 4, an eccentric or cam shaped clamp 6, the weighted end of which is adapted to be held by gravity against the face of the attaching plate, engaging therewith along a line some distance below the lower edges of the horizontal members 7 of the bracket

arms. The cam is provided with an extension 5, which when the clamp is in normal position as represented in the drawings lies beyond the outer edges of the depending parts of the bracket arms. This extension 5 constitutes readily accessible means by 55 which the clamp may be manipulated. In use the article to be held between the weighted end of the clamping cam 6 and the plate 1 is slipped between these two parts until it is arrested by coming into engagement with 60 the lower edges of the horizontal members 7 of the bracket arms. These are so positioned that the article when thus arrested is in proper position to be securely held by the clamping cam. As has been stated the clamp 65 described is particularly adapted for supporting maps, charts and the like and it is desirable that these should be supported with their upper and lower edges horizontal. This can be easily secured by use of clamps 70 such as I have illustrated provided they be properly applied to the wall surface or other support on which they are carried. In applying to a map or chart it is only necessary that the upper edge thereof be slipped 75 into two clamps simultaneously and until such edge engages the stops above the clamping cam formed by the horizontal portions of the bracket arms. These stops thus serve as means, not only for determining the 80 proper points of engagement for the clamping cams, but also for insuring that the article if supported by two clamps shall be properly suspended with reference to the horizon.

85 The frame comprising the attaching plate 1 and the bracket arms 3 is preferably formed from an integral piece of sheet metal cut and shaped to produce the article illustrated in the drawings.

90 What I claim is:

A clamp for holding suspended maps, charts and the like, comprising an attaching plate, a pair of bracket arms extending outwardly from the upper end thereof, the 95 ends of the bracket arms depending and being substantially parallel with the attaching plate, and a clamping cam pivotally sup-

ported in the lower ends of the depending portions of the bracket arms, arranged to have its weighted end bearing by gravity against the front face of the attaching plate 5 along a line below the lower edges of the outwardly extending portions of the bracket arms, which portions serve as stops to arrest

an article being applied to the stop, and determining the proper position in which it should be held by the clamp.

10

In testimony whereof I hereunto affix my signature.

NEWELL D. PARKER.
